R. F. DAVIS

PROCESS OF TREATING PETROLEUM OILS

Filed Aug. 15, 1922

Inventor
Richard F. Davis
By Lyon & Lyon Atty

UNITED STATES PATENT OFFICE.

RICHARD F. DAVIS, OF EL SEGUNDO, CALIFORNIA, ASSIGNOR TO STANDARD OIL COMPANY, OF SAN FRANCISCO, CALIFORNIA, A CORPORATION OF CALIFORNIA.

PROCESS OF TREATING PETROLEUM OILS.

Application filed August 15, 1922. Serial No. 581,956.

To all whom it may concern:

Be it known that I, RICHARD F. DAVIS, a citizen of the United States, residing at El Segundo, in the county of Los Angeles and State of California, have invented a new and useful Process of Treating Petroleum Oils, of which the following is a specification.

This invention relates to a process of treating distillates which have been obtained from the cracking or destructive distillation of petroleum oils, and while not necessarily confined thereto, refers more particularly to the treatment of the cracked distillates from California or asphaltic base crudes.

Distillates which are obtained from cracking or destructive distilling operations differ materially from the natural distillates obtained from the same oil. These distillates are generally more unsaturated, that is, contain more unsaturated and unstable constituents, contain larger percentages of gum and tarry material and present to the refiner a problem which is difficult if at all met by such processes as are now in use. To refine these distillates in the customary manner, with sulphuric acid, requires a large quantity of sulphuric acid and involves a large loss of the distillates.

I have discovered that this loss of desirable distillates and the use of acid can be minimized and a much more desirable product obtained by treating these distillates in a process which will be herein described.

Generally, the object of this invention is to produce a motor fuel from distillates obtained in a cracking process, which motor fuel will pass all quality and stability tests specified in the Bureau of Mines Bulletin No. 305.

An object of this invention is to produce a more economical process for refining these distillates.

Specifically, the objects of this invention are: (1st) to minimize the use of sulphuric acid; (2nd) to minimize refining losses; (3rd) to remove organic acids, both those inherent in the distillate and resulting intermediate in the process; (4) to remove all the easily oxidizable materials; (5th) to remove the constituents in the distillate which dissolve metal; (6th) to improve the color; (7th) to stabilize the oil so that it will not tend to form gums or acquire color; (8th) to employ a controllable oxidation in

place of the action of sulphuric acid; and (9th) to provide a process which may be conducted in the equipment in ordinary use at a refinery without necessitating expensive changes in that equipment.

I have found that by treating these distillates with copper oxide, the undesirable constituents unite with the copper oxide to form oil soluble material which may be separated from the oil, leaving the oil in a highly refined and suitable condition, by simple distillation of the oil from these compounds. The action of the copper oxide on these materials is greatly accelerated if not dependent upon the presence of light which may be diffused day-light, sun-light or artificial light, preferably containing a high percentage of ultra violet rays. The action of the light on the oil in the presence of metal oxides is photo-chemical whereby the undesirable constituents are oxidized to organic acids which act with the metal oxide forming corresponding metal salts. The treatment with copper oxide can be carried out on the cold oil by agitating the oil with finely divided copper oxide, whereby sufficient of the copper oxide will be dissolved in the oil to unite with those constituents undesirable in a high quality of motor fuel and that the oil containing the dissolved copper may then be readily separated by decantation or other means, whereby only the copper oxide which is essential to the treatment will be consumed and the remaining oxide will be maintained in a condition proper for further treating said distillate.

My process should not be confused with some of the older processes which treat normal paraffine base distillates, which contain a large percentage of sulphur and are called "shunk oils", and are employed for the removal of sulphur. The action of copper oxide in my process is distinctly different from these prior processes. My process is conducted upon a different material, i. e., a cracked distillate, is conducted in a different manner, is greatly facilitated by the action of light, and produces results entirely different from those of the prior processes. It is especially to be noted that these prior processes are conducted only upon "shunk oils" for the removal of sulphur. In my process there is no material reduction in the sulphur content by the copper oxide treatment.

I have further discovered that this copper oxide treatment may be materially aided by first treating the distillate with a small quantity of sulphuric acid. Apparently, the action of this sulphuric acid is to remove sulphur containing constituents.

With the foregoing preliminary explanation my invention will be more readily understood by reference to the accompanying drawing, illustrating diagrammatically an apparatus for conducting copper oxide steps of my process.

Referring to the drawing, 2 represents an agitating tank which is preferably either open at the top or closed with glass or other light diffusing material. 1 indicates an oil charging line, 9 indicates a draw-off line connecting to the bottom of said agitating tank. A conveyor 3 is provided, connected to a supply of copper oxide (not shown), which leads to the agitating tank 2. Said tank 2 is provided with a swing pipe 4 which is connected by a line 5 containing a valve 21 to a pump 6. The pump 6 is connected through a T-connection 22, first through the line 25 containing the valve 7 to a perforated line 8, in the agitating tank 2; and second, through a line 10 containing valves 23 and 24 to a still 11. The still 11 is provided with a draw-off line 20; a vapor line 12 and a steam coil 26 connected by a line 27 to a source of steam. The vapor line of the still 11 leads to a condenser coil 13 surrounded by a condenser box 16. The condenser coil 13 is connected by a line 17 to a receiving tank 18. The condenser box 16 is provided with a line 14 connected to a source of water (not shown) for supplying cooling water to the condenser coil 13 and said condenser box 16 is further provided with a flow off line 15, through which the water is discharged.

In operation of the process the distillate before or after such preliminary treatment, as will be later described, is introduced into the agitating tank 2 through the line 1. A suitable quantity of finely divided copper oxide is supplied by the conveyor 3. The copper oxide referred to in this specification is preferably cupric oxide. Valve 23 is closed, valves 21 and 7 are opened and the copper oxide and distillate are agitated by circulation through the lines 4, 5, 25 and 8 by operation of the pump 6. This agitation is continued until all the undesirable constituents have united with the copper oxide forming oil soluble constituents. Light enters through the top of the agitating tank 2 and materially aids in the oxidizing or photo-chemical action.

The contents of the agitating tank 2 are allowed to settle and then pumped by the pump 6 to the still 11, valves 21, 23, 24 being open and the valve 7 being closed. The oil is then distilled from the soluble copper compounds by any of the usual heating means,

preferably by the injection of steam through the line 27 and coil 26. The vapors passing through the vapor line 12 are condensed in the coil 13 and pass to the storage tank 18. The distillate will then be found to be of very high quality.

The preliminary treatment of the distillate before referred to may be conducted in a number of different ways and has a marked effect upon the copper oxide treatment. The effect of this preliminary treatment is apparently to remove the sulphur constituents of the oil. In general there are two manners in which this preliminary treatment may be conducted.

In the first method, the distillate is treated with caustic soda; the caustic soda separated from the oil and the oil then treated with a small amount of concentrated or fuming sulphuric acid. The acid sludge is then separated from the oil, the oil neutralized and then introduced into the tank 2. Apparatus for conducting these steps is well known in the art and need not be described. The preliminary treatment with caustic soda in this process apparently prevents the fixing of the sulphur compounds by the concentrated fuming sulphuric acid, and apparently serve to remove a large portion of the sulphur containing constituents.

The second and preferred method of preliminary treatment does not require a preliminary caustic soda treatment of the oil but the action is accomplished by the use of a much weaker acid. Preferably I add to a gallon of oil $\frac{1}{4}$ of a pound of 58° Baumé sulphuric acid containing approximately 75% sulphuric acid, although various strengths of acid may be used. The resulting acid is drawn off, the distillate neutralized by well known methods and introduced into the agitating tank 2.

It is understood that the foregoing described process is only illustrative of the preferred embodiment of my invention and my invention is not limited to the preferred embodiment but various changes may be made in the process such as substitution of other oxides for the copper oxide without departing from the spirit of my invention.

My invention is of the scope set forth in the following claims.

I claim:

1. A process of purifying petroleum oils which includes subjecting the oils to the action of copper oxide under the influence of light.

2. The process of purifying petroleum distillates which includes agitating the distillates, in the presence of light, with copper oxide until the resultant action is complete, and separating the oil from the undissolved oxide and the dissolved copper compounds.

3. A process of purifying petroleum oils which includes removing the unstable sul-

phur containing constituents by treatment with sulphuric acid and caustic soda, treating said oils with copper oxide in the presence of light until the resultant action is 5 complete, and separating the oil from the undissolved copper oxide and the dissolved copper compounds.

4. A process of treating a petroleum oil to remove from the oil those constituents 10 which dissolve metals, which process includes subjecting the oil to the action of copper oxide carried out at a temperature substantially lower than the boiling temperature of the oil and under the influence of 15 light, so that oil soluble compounds are

formed with the copper oxide, and thereafter separating from the admixture the purified oil.

5. A process of refining petroleum oils which includes first removing from the oils 20 sulphur compounds by treatment with sulphuric acid and a neutralizing agent, then subjecting the oil in the cold state to the action of copper oxide under the influence of light, and separating from the mixture 25 the purified oil.

Signed at El Segundo, Calif., this 7th day of August, 1922.

RICHARD F. DAVIS.
